HEAT EXCHANGER

Richard A. Sharp, Milwaukee, Wis., assignor to
 Milwaukee Reliance Boiler Works, Milwaukee,
 Wis., a corporation of Wisconsin

Application February 28, 1935, Serial No. 8,663

5 Claims. (Cl. 122—33)

This invention relates to improvements in heat exchangers and refers more particularly to apparatus for heating bituminous material of all types and especially asphalt, tar, and road oils used in paving. These materials are transported in tank cars and obviously must be heated to give them sufficient fluidity to enable removal thereof from the tank cars.

To this end, the cars are generally provided with steam coils connectible with an external source of steam. In the past, it has been the custom merely to provide some form of steam generating boiler either portable or semi-portable and to run the steam generated thereby through the coils in the tank car.

In some instances, provision was made for returning the condensate back into the boiler to prevent wasting the water, but in many instances, the spent heating medium was merely exhausted into the atmosphere.

This past method of handling such highly viscous materials was far from satisfactory. The operation of the boiler to provide sufficient steam for bringing the material to the proper degree of fluidity was costly, and in many instances boosters had to be employed in conjunction with the primary heating means which obviously further increased the cost. Boosters developed for this purpose were in the form of fire tube boilers through which in place of water content, the material to be heated was circulated by means of pumps which because of the nature of the material being handled had to be of expensive construction.

With these objections to the existing methods and apparatus for handling bituminous materials in mind, it is a general object of this invention to provide a single unitary structure which provides not only an adequate supply of steam for heating the material within the tank car, but also contains within itself all the elements of a booster so that the heating of the material and maintaining it in a proper state of fluidity is effected at a minimum cost both in initial outlay and in operation.

More specifically it is an object of this invention to provide a combined steam boiler and heat exchanger having independent sets of tubes, one of which provides for the circulation of a heating medium, and the other for the circulation of the material to be heated.

Another object of this invention is to provide a unit of the character described which is of simple compact mechanical construction and wherein the partitions separating the two circulation

systems are so constructed that the content of the boiler is utilized as insulation obviating the use of refractory materials.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawings illustrate one complete example of the physical embodiment of the invention constructed according to the best mode so far devised for the practical application of the principles thereof, and in which:

Figure 1 is a longitudinal section view through a unit embodying this invention;

Figure 2 is a cross section view taken through Figure 1 on the plane of the line 2—2;

Figure 3 is a cross section view taken through Figure 2 on the plane of the line 3—3; and

Figure 4 is a diagrammatic view illustrating the invention in use.

Referring now more particularly to the accompanying drawings in which like numerals indicate like parts throughout the several views, the numeral 5 designates the outer shell of the unit. The ends of the outer shell, which is preferably cylindrical, are closed by end walls 6 and 7, and spaced inwardly from the end walls 6 and 7 are partitions 8 and 9, respectively.

The partitions 8 and 9 together with the end walls and the end portions of the outer shell define headers 10 and 11, respectively. The space within the shell between the partitions 8 and 9 forms a boiler adapted to contain water for the generation of steam. This boiler space is preferably provided with a port 12 with which steam lines may be connected. A water inlet port 13 (not shown in Figure 1 but indicated in Figure 4) and a drain or blow-off 13' are also provided.

The headers 10 and 11 are divided into separated upper and lower chambers 14 and 15 and 16 and 17, respectively, by transverse horizontal partitions 18 and 19, respectively. These partitions 18 and 19 are of similar construction and comprise two parallel spaced plates 20 and 21 having their side edges attached to the end walls and the partitions and having their end walls attached to the cylindrical outer shell. Stay bolts 22 connect the plates 20 and 21 to add rigidity thereto.

The partition walls 8 and 9 opposite the partitions 18 and 19, respectively, are either cut away

entirely, as shown at 23, or may be provided with ports through which the space within the hollow partitions 18 and 19 is communicated with the boiler space containing the water so that the 5 water is free to enter the hollow partitions 18 and 19 which thus become water legs. Obviously, the water level within the boiler must be maintained higher than the partitions 18 and 19.

With the partitions 18 and 19 constructed in 10 this manner so as to utilize the water contents of the boiler as a heat insulating medium, the upper and lower chamber or compartments of the headers are positively separated from each other without the need for refractory linings on the 15 partitions 18 and 19.

Connecting the lower compartments 15 and 17 of the headers 10 and 11, respectively, is a main fire tube 24. Leading to the fire tube 24 at the header 11 and forming substantially a continuation thereof through the header 11 is an inlet passage 25 preferably formed of refractory material and having its ends securely anchored to the partition wall 9 and the adjacent end wall 1. Both these walls have openings in line with the 20 inlet 25 so that a heating medium either in the form of a flame projected from an oil burner or any other suitable medium may be introduced 25 into the fire tube 24.

The opposite end of the fire tube 24 opens to 30 the lower chamber 15 of the header 10. In line with this end of the tube is a refractory barrier 26 covering the end wall 6 against which the flame or other heating medium projected through the tube 24 impinges. Directly beneath the point of 35 communication between the fire tube 24 and the lower chamber 15 is a refractory barrier 27 and to one side thereof is another refractory barrier 28. These barriers extend across the lower chamber 15 of the header 10 to divide the same into separated compartments 29 and 30.

40 A plurality of fire tubes 31 connects the lower chambers 15 and 17 of the headers 10 and 11, respectively, beneath the partitions 18 and 19. The ends of these tubes are anchored in the partition walls 8 and 9 as is customary and open to the chambers 15 and 17. Some of these tubes communicate with the compartment 29 and others communicate with the compartment 30 at their ends secured to the partition wall 8.

50 Within the lower chamber 17 of the other header 11 is a transverse horizontal partition 32 in line with the partition 27 which divides the chamber 17 into an upper compartment 33 and a lower compartment 34. Through the provision 55 of these baffles or partitions within the lower chambers 15 and 17, the heating medium is caused to flow back and forth through the tubes 31 so that the heating medium makes a plurality of passes back and forth, and while the structure shown 60 provides for four passes, or may be termed a four pass boiler, an arrangement providing for a greater or lesser number of passes as the size of the unit may dictate can be employed.

The spent heating medium is exhausted from 65 the header 11 through an exhaust port 35 in the end wall 7.

The lower portion of the unit is thus substantially a fire tube steam boiler which because of its multiple pass construction has exceptionally 70 high efficiency.

75 The upper portion of the unit above the partitions 18 and 19 comprises a heat exchanger through which the material to be heated is circulated. This heat exchanger is substantially like the lower boiler section of the unit and com-

prises the upper chambers 14 and 16 of the headers 10 and 11, respectively, and a second plurality of tubes 36 connecting these upper chambers.

An inlet port 37 leading to the chamber 14 and carried by the end wall 6 provides for the entrance of the material to be heated and an outlet port 38 leading from the chamber 16 and carried by the end wall 7 provides for its discharge.

The chambers 14 and 16 are provided respectively with transverse partitions 39 and 40 which 10 divide the chambers 14 and 16 into compartments and form baffles to cause the material being heated to flow back and forth through the tubes 36, as will be readily apparent.

15 From the description thus far, it will be apparent that this invention provides a combined steam boiler and heating unit capable of many uses, and while not limited to the heating of bituminous and similar heavy viscous materials used in paving, to enable the pumping thereof 20 from tank cars into transport trucks, it is admirably suited to this purpose and in Figure 4 the use of the invention in this manner is diagrammatically illustrated.

As here shown, the combined boiler and heat 25 exchanger provides motive power for operating a steam pump 41 by which the material being handled is pumped from a tank car 42 through the heat exchanger and either back into the tank car or into a transport truck 43.

30 A steam line 44 connecting the steam jacket of the unit with the pump 41 provides for the operation of the pump, and a second steam line 45 leading from the steam jacket of the unit to the inlet of the steam coils in the tank car 35 supplies steam to the coils. The outlet end of the coils has a return line 46 connected thereto, in which a steam trap 47 is interposed. A condensate return pump 48 also connected in the line 46 returns the condensate to the boiler.

40 The pump 41 has its inlet connected with the tank car by a pipe line 49 and its discharge port connected with the inlet 37 of the heat exchanger by a pipe line 50. The outlet 38 of the heat exchanger is connected by a line 51 with a three 45 way valve 52. Also connected with the three way valve 52 is a line 53 leading to the transport truck, and a line 54 leading back to the tank car 42.

50 Hence, through control of the valve 52, the contents of the tank car may be pumped into the transport truck after being passed through the heat exchanger or may be continuously circulated from the tank car through the heat exchanger and back into the tank car.

55 As noted hereinbefore, this is but one manner of using the invention and is described merely for purposes of illustration. Other uses and adaptations of the combined steam boiler and heat exchanger unit will suggest themselves to 60 those skilled in the art to which this invention appertains.

65 What I claim as my invention is:

1. A heat exchanger comprising an outer shell, walls closing the ends of the shell, partition walls 65 spaced inwardly from the end walls and cooperating therewith to define headers, a plurality of tubes connected at their ends with the partition walls and communicating the headers, means to divide each header into separated chambers, said 70 separated chambers of the headers together with the tubes communicating the same providing for the circulation of a heating medium and a fluid to be heated, one of the tubes for the circulation of the heating medium being of large 75

- diameter, means forming substantially a continuation of said tube and passing through one of the headers so that said tube has an open communication with one end of the unit to provide a 5 combustion chamber into which the heating medium is initially introduced, and the space within the shell and around the tubes forming a container for a heat transfer medium to facilitate the transmission of heat from the heating 10 medium to the fluid to be heated.
2. A combined steam boiler and heat transfer unit comprising an outer shell, a closed header at each end of the shell, a partition dividing each header into separated chambers, a plurality of 15 tubes connected at their ends with one of each of the two chambers into which each header is divided, said tubes and the chambers communicated thereby providing passages through which a heating medium may be circulated, one of said 20 tubes for the circulation of the heating medium being larger in diameter than the rest, a tubular extension forming substantially a continuation of said larger tube through one of the headers to provide an inlet for the heating medium so 25 that said larger tube forms an initial combustion chamber, a second plurality of tubes connected at their ends with the other chamber of each header, said second plurality of tubes together with the header chambers which they 30 communicate affording passages through which a fluid to be heated may be circulated, and the space within the shell not occupied by said tubes affording a container for a heat transfer medium to facilitate the transmission of heat from 35 the heating medium to the fluid to be heated.
3. In a heat exchanger of the character described, an outer shell, a hollow header closing each end of the shell, said headers having outer and inner walls, a partition dividing each header into separated chambers, a plurality of fire tubes 40 having their ends connected with the inner walls of the headers beneath the partitions in the headers to communicate the lower chambers thereof, one of said fire tubes being larger in diameter than the rest and having an extension at one end directly through the adjacent hollow header so as to provide an inlet into which the heating medium may be directly injected and whereby said larger diameter tube forms an initial combustion chamber, baffles in said lower 45 chambers to direct a heating medium injected into said fire tubes back and forth through said fire tubes, an exhaust leading from one of said lower chambers of one of the headers through 50 which spent heating medium is exhausted, a second plurality of tubes having their ends connected with the inner walls of the headers above the partitions in the headers to communicate the

upper chambers thereof, baffles in the upper chambers of the headers to direct the flow of fluid to be heated back and forth through said second set of tubes, an inlet leading to the upper chamber of one of the headers to provide for the 5 entrance of fluid to be heated, and an outlet from one of the upper chambers of one of the headers for the fluid to be heated, the space within the outer shell not occupied by said tubes providing a container for water and a jacket for steam developed upon heating of the water. 10

4. A heat exchanger of the character described comprising an outer shell, a hollow header closing each end of the shell, each header having an inner wall and an outer wall, a hollow partition 15 dividing each header into separated chambers, the inner walls of the headers being open to communicate the interior of the hollow partitions with the interior of the outer shell so that water contained within the outer shell is free to 20 enter the hollow partitions, a plurality of fire tubes having their ends connected with the inner walls of the headers beneath the hollow partitions to cooperate with the lower chambers of the hollow headers and provide passages through 25 which a heating medium may be circulated, and a second plurality of tubes connected to the inner walls of the headers above the hollow partitions to cooperate with the upper chambers thereof and provide means through which a fluid to be 30 heated may be circulated.

5. A combined steam boiler and heater for viscous materials comprising an outer shell, a hollow header at each end of the shell, each header having an inner wall and an outer wall, a partition 35 dividing each header into separated chambers, a plurality of fire tubes having their ends connected with the inner walls of the headers at one side of the partitions to cooperate with the header chambers at that side of said partitions 40 to provide for the circulation of a heating medium, one of said fire tubes being larger in diameter than the others, and the outer and inner walls of one of the headers having aligned openings of substantially the same diameter as said 45 larger tube, a tubular member of refractory material extending across said header in line with said openings to form substantially a continuation of said larger tube and provide an inlet leading thereto through which a heating medium may 50 be injected directly into said larger tube for circulation through said fire tubes, and a second plurality of tubes connected to the inner walls of the headers on the other sides of said partitions to cooperate with the header chambers at 55 that side of the partitions to provide for the circulation of a fluid to be heated.

RICHARD A. SHARP.
